ANTENNA

Milton Spirt, New York, N. Y.

Application April 19, 1949, Serial No. 2,145

Term of patent 7 years

(Cl. D26—14)

To all whom it may concern:

Be it known that I, Milton Spirt, a citizen of the United States, residing at New York, in the county and State of New York, have invented a new, original, and ornamental Design for an Antenna, of which the following is a specification, reference being had to the accompanying drawing, forming part thereof.

Fig. 1 is a front elevation of an antenna embodying my new design;

Fig. 2 is an edge view thereof; and

Fig. 3 is a top plan view of the same.

I claim:

The ornamental design for an antenna, substantially as shown.

MILTON SPIRT.
